SKEG FOR BARGES AND LIKE VESSELS

George R. Taylor, Woodlynne, N. J., assignor to
 John H. Mathis Company, Camden, N. J., a
 corporation of New Jersey

Application December 6, 1933, Serial No. 701,095

8 Claims. (Cl. 114—140)

The invention is designed to improve the towing qualities of barges or other like vessels, more particularly those of the rake end type, as well as to afford certain other advantages over skegs of conventional form.

It is known that the tendency of a barge or other towed vessel to follow the course of the tug is enhanced in proportion to the amount of drag adjacent the stern, and as a consequence barges employing conventional skegs have therefore frequently been built with very blunt sterns to thereby increase the drag adjacent thereto with a view to maintaining the barge on a proper course while it is being towed. A stern of this character, however, causes the barge to tow hard, with the result that for a given expenditure of towing power the barge cannot be moved as rapidly as one having less stern drag so that the time required for taking the barge from port to port is increased, or, if better time is to be made, more power must be used, whereby the expense of operating the barge is increased either because of the length of time required for a given voyage or the amount of power necessary to accomplish it in a given time.

The principal object of the present invention, therefore, is the provision of a skeg of novel design and construction which is effective when the barge tends to deviate from its course to present a progressively increasing drag or resistance to its turning or sluing movement and thereby cause it to return to its true course.

A further object of the invention is the provision of a novel skeg through the use of which the necessity of abnormally increasing through hull design the drag adjacent the stern of a barge or like vessel in order to make it properly follow the tug is obviated, which reduces the power required to tow the barge to which it is attached considerably below that required to tow under like conditions a similar barge having a skeg of conventional type but whose hull is designed to afford sufficient stern drag to maintain it properly upon its course.

A still further object of the invention is the provision of a skeg of the character aforesaid for use in place of the conventional skeg hitherto customarily employed, which is advantageous in that it adds to the structural strength of the barge; is capable of sustaining its proportion of load should the barge ground at any time; is of such design that it can be economically manufactured and installed either in new barges or in place of conventional skegs in existing barges; which can be installed either singly or in multi-

ple in accordance with the preference of the barge designer or to better meet the conditions of service to which the barge is subjected; which displaces its own weight of water or can be made to displace more than its own weight, if desired, when the vessel is loaded, and which is stiffer and stronger than ordinary skegs adapted for installation under generally similar conditions.

Other objects, advantages and novel features of design, construction and arrangement comprehended by the invention are hereinafter more particularly pointed out or will be apparent to those skilled in the art from the following description of a preferred embodiment thereof as illustrated in the accompanying drawing, in which Fig. 1 is a fragmentary side elevation of the stern of a barge of the rake-end type equipped with one of my improved skegs; Fig. 2 is a fragmentary stern view thereof, and Fig. 3 is a horizontal section of the skeg substantially on the staggered line 3—3 in Fig. 1. Like characters of reference are employed to designate the same parts in the several figures.

More particularly and as shown, my improved skeg in its preferred embodiment comprises a main plate 1 of steel or other suitable metal of generally triangular form, the longest edge 2 of the plate being shaped to snugly conform to the curvature of the bottom *b* of the barge *B* as it rises toward the transom *t* while the other edges 3, 4 preferably respectively extend in parallelism with and prolongation of the keel or major portion of the bottom of the barge and substantially vertically.

The main plate forms the backbone of the skeg and is provided on each side with one or more hollow fins longitudinally spaced along the plate when more than one fin is employed. Under most conditions three such fins may desirably be utilized as shown in the drawing, in which the port fins, shown in Fig. 1, are designated as *F*, *F'*, *F''*, and the corresponding starboard fins as *F¹*, *F²*, *F³*.

Each fin is preferably composed of a pair of generally V-shaped plates 6, 7 disposed in opposite angular relation to the main plate 1 and extending from its lower edge 3 upwardly to the hull of the barge, each plate having longitudinal edges 8, 9 respectively adapted to lie adjacent the corresponding edge of the other plate and adjacent the main plate 1 when the parts are assembled. In the construction shown, the angle included between these edges is a little greater in the case of the plate 6 than in that of the plate 7, but as the latter is some-

what longer than the former, since both plates are carried up far enough to engage the bottom of the barge to which they are ultimately tightly welded, the respective areas of the two plates do not differ greatly under these conditions. However, it may sometimes be preferred to make the angle between the edges 8, 9 of the plates the same for both, or even to make the angle less in the forward plate than in the stern one, the particular relationship between the said angles being largely a matter of choice with the designer. The upper ends of both plates are of course so shaped that they will seat snugly against the bottom of the barge, while at their lower extremities the plates are preferably cut off transversely in a plane coincident with the bottom of the main plate 1 and thus short of the point at which the edges 8, 9 would intersect if prolonged, and the ends of the plate are ultimately welded to a small generally rectangular keeper plate 10 which seats in a suitable notch 11 cut in the bottom edge of the main plate and welded or otherwise secured in position therein, thus closing the lower end of the fin. The edges 9, 9 are also during assembly welded to the main plate and the edges 8 welded together so as to form a fully watertight structure which in horizontal section at any point between the lower edge of the main plate and the lower point at which the fin contacts the barge bottom approximates an isosceles triangle.

Preferably in direct transverse alignment with each such fin, a corresponding fin is provided on the other side of the main plate as best shown in Fig. 3; thus, the fins in the finished skeg are arranged symmetrically in opposed relation on opposite sides of the main plate, the longest fin being adjacent the stern end of the latter and the shortest fin, if a plurality of them are employed, being adjacent its bow end.

Each corresponding pair of fins may be therefore considered as approximating an inverted hollow truncated pyramid tapering downwardly from the barge bottom to the lower edge of the skeg and intersected longitudinally and centrally by the main plate 1; while under usual conditions three fins may desirably be provided on each side, any suitable number or even, in some cases, but a single fin on each side of the main plate may be utilized.

Under actual conditions of operation it has been found that a barge provided with one or more of my improved skegs tows relatively easily and tends to very accurately follow the course of the tug, and I attribute this to the fact that when the barge tends to slew or otherwise depart from its proper course, a progressively increasing pressure is rapidly exerted by the water on the plates 6 constituting the forward plates of the fins on that side of the skeg toward which the stern of the barge tends to move and a generally corresponding suction or retarding force on the adjacent plates 7 with the result that the stern is swung back toward proper position, that is, one in which the skeg is in substantial alignment with the course of the tug. When in this position equal pressures are of course exerted on both sides of the skeg and on the fins and the barge therefore tows most easily when in that position and consequently tends to remain therein rather than to depart therefrom. It is, of course, well understood that a barge provided with a conventional skeg tends to follow the course of the tug better than one having no skeg at all but in the case of a conventional skeg but very

little resistance is afforded to slewing or swinging of the barge stern until the barge reaches a very considerable angle with respect to the true course. With my improved skeg, however, resistance in opposition to the swinging or slewing of the stern is applied quickly, effectively and progressively whenever the barge tends to depart from the true course, and the barge is therefore automatically returned thereto before it can depart to any considerable extent therefrom. The power exerted by the towing vessel is therefore effectively utilized in pulling the barge ahead along the proper course and not in large part wasted in merely returning the barge thereto after each material departure therefrom.

It will be apparent from the foregoing that my improved skeg is relatively inexpensive to construct and may be readily applied to new barges when they are being built or to existing barges and like vessels in place of the present conventional skegs with which they are now equipped and, further, that the skeg as a whole presents a stiff unitary structure capable of sustaining a fair proportion of the total weight should the barge become stranded or go aground. Under certain conditions, moreover, a single piece of metal may be bent to form each fin instead of providing two separate plates and welding them together along their edges 8, while, if preferred, any or all of the edges of the fins, irrespective of their specific construction, could be flanged out and riveted to the main plate, bottom of the barge and/or other parts with which they are in engagement and the seams caulked in accordance with the practice usual in riveted ship construction, though generally it will be found more convenient and cheaper to weld the various parts together.

It will of course be appreciated that the barge may be provided with but one of my improved skegs disposed on its center line as shown in the drawing or with a plurality of such skegs spaced at suitable distances apart, as for example, a pair of skegs disposed one under each quarter, or three skegs disposed one on the center line and one under each quarter in accordance with customary practice.

While I have herein described one form of my invention with considerable particularity, I thereby do not desire or intend to specifically limit or confine myself thereto as various changes and modifications may be made in the form and arrangement of the elements employed, in their method of assembly and in other particulars without departing from the spirit and scope of the invention as defined in the appended claims.

Having thus described my invention, I claim and desire to protect by Letters Patent of the United States:

1. In a barge or like vessel, a skeg comprising a main plate provided on each of its sides with a fin having outer faces oppositely angularly disposed to the plate and to each other.

2. In a barge or like vessel, a skeg comprising a main plate provided on each of its sides with a fin having outer faces oppositely angularly disposed to the plate and to each other, the upper end of each fin engaging the bottom of the barge and the lower end terminating adjacent the bottom of the plate.

3. In a barge or like vessel, a skeg comprising a main plate extending generally fore and aft and having on each of its sides a hollow fin having outer faces disposed in angular relation to each other, each fin extending from the bottom of the

- barge to a point adjacent the bottom of the plate and forming watertight joints with said bottom and said plate, and means for preventing the entrance of water to the lower end of each fin. 80
- 5 4. In a barge or like vessel, a skeg comprising a main plate extending generally fore and aft and having on each of its sides a hollow fin having outer faces disposed in angular relation to each other, each fin extending from the bottom of the barge to a point adjacent the bottom of the plate and forming watertight joints with said bottom and said plate, and means for preventing the entrance of water to the lower end of each fin, the fins on the opposite sides of the plate being arranged in transversely aligned relation. 85
- 10 5. In a barge or like vessel, a skeg comprising a main plate extending generally fore and aft and having on each of its sides a hollow fin having outer faces disposed in angular relation to each other and to the plate, each fin extending from the bottom of the barge to a point adjacent the bottom of the skeg and having its edges welded to said bottom and to said plate to form watertight joints therewith, and means for preventing entrance of water to the interior of the fin at its lower end. 90
- 20 6. In a barge or like vessel, a skeg comprising a main plate extending downwardly from the bottom of the barge to a point substantially in the plane of its keel and having on each side a fin in 95
- 25 7. In a barge or like vessel, a skeg comprising a main plate provided on each of its sides with an immovable, generally vertically extending fin having outer faces oppositely angularly disposed to the plate and to each other, each plate progressively narrowing from adjacent the bottom of the vessel to a point adjacent the bottom of the plate. 100
